[57] CLAIM

The ornamental design for a combined tool holder and cutting inserts therefor, as shown and described.

DESCRIPTION

FIG. 1 is a top view of a combined tool holder and cutting inserts therefor embodying my new design;

FIG. 2 is a front view thereof;

FIG. 3 is a side view taken from the left of FIG. 1;

FIG. 4 is a side view taken from the right of FIG. 1;

FIG. 5 is a bottom view thereof;

FIG. 6 is an inverted rear view taken from the top of FIG. 1;

FIG. 7 is a top view of a second embodiment of my new design;

FIG. 8 is a side view taken from the left of FIG. 7;

FIG. 9 is a side view taken from the right of FIG. 7;

FIG. 10 is a bottom view of FIG. 7.

The front and rear views of the second embodiment are identical to the front and rear views of the first embodiment shown in FIGS. 2 and 6.
